UNITED STATES PATENT OFFICE.

DEMARIAN L. O'NEAL, OF VALDOSTA, GEORGIA.

TURPENTINE-CUP.

1,019,183.

Specification of Letters Patent.

Patented Mar. 5, 1912.

Application filed July 26, 1911. Serial No. 640,718.

To all whom it may concern:

Be it known that I, DEMARIAN L. O'NEAL, a citizen of the United States, residing at Valdosta, in the county of Lowndes and 5 State of Georgia, have invented a new and useful Turpentine-Cup, of which the following is a specification.

This invention relates to metallic turpentine cups of that type formed of sheet metal. 10 Cups of this type, as heretofore constructed, have been found objectionable for various reasons among which may be mentioned the fact that after a cup has been used for a short time the folds thereof begin to gape, 15 this being due to the weight of the contents of the cup and to the pressure of the paddle used for scraping or dipping the turpentine from the cup and into a suitable receptacle. Moreover cups such as heretofore devised 20 have not been so shaped as to be readily held in one hand while turpentine is being poured and scraped therefrom.

One of the objects of the present invention is to provide a sheet metal cup the folds of 25 which are so arranged as to be held positively against gaping, the interior of the cup being free of abrupt angles so that a paddle or scraper can be used for thoroughly clearing the cup of turpentine.

30 A further object is to provide a sheet metal cup the outer faces of which are rounded or convex so as to be easily and comfortably held in the hand while the turpentine is being removed from the cup.

35 With the foregoing and other objects in view which will appear as the description proceeds, the invention resides in the combination and arrangement of parts and in the details of construction hereinafter described 40 and claimed, it being understood that changes in the precise embodiment of the invention herein disclosed can be made within the scope of what is claimed, without departing from the spirit of the invention.

45 In the accompanying drawings, the preferred form of the invention has been shown.

In said drawings:—Figure 1 is a front elevation of the cup and its apron connected to a portion of a tree. Fig. 2 is a section on 50 line A—B Fig. 1. Fig. 3 is a rear elevation of the cup. Fig. 4 is a plan view of the cup. Fig. 5 is a detail view of the blank from which the cup is formed.

55 Referring to the figures by characters of reference 1 designates a blank of sheet metal adapted to be folded longitudinally as indi-

cated by the dotted line *a* in Fig. 5. One longitudinal edge of the blank is then folded along a curved line, as indicated at *b* to form a retaining and reinforcing flap 2. 60 The blank is then folded along the line *c*, Fig. 5, so as to form a reinforcing strip 3 extending longitudinally of the blank. The lower corner portions of the folded blank are then folded back along diagonal lines, 65 as indicated at *d* so as to form triangular flaps 4, each of a double thickness, the upper edges of the flaps being lapped and retained against the adjacent portions of the blank, by the flap 2. The lower corner portions 70 of the flap 2 project beyond the folds 4 so as to form triangular clips 5 and these clips are adapted to be bent along diagonal lines, as indicated at *e* so as to lap the end portions of the reinforcing strip 3. It will 75 be apparent that the cup thus produced by folding the blank 1 has a substantially flat rear wall the upper edge of which is extended upwardly above the upper edge of the bowed or curved front wall of the cup. 80 Furthermore it will be seen that the triangular flaps 4 are prevented from gaping open because they are held tightly against the rear wall of the cup by the flap 2 which, in turn, is held in retaining position by the 85 clips 5 extending across the upper corners of the front wall of the cup. It will, furthermore, be noted that the front and rear walls of the cup do not form acute angles where they come together but, instead, the 90 inner surface of the cup is rounded where the two walls merge together. The outer surface of the cup is correspondingly rounded and it will be seen that said cup can be readily and comfortably held in the hand 95 while a scoop or other instrument is being used for scraping turpentine from the cup. As there are no acute angles within the cup, it will be apparent that a scraper or scoop can be used efficiently for removing all of 100 the turpentine from the cup whereas, should the walls form acute angles where they come together, it would be difficult to thoroughly clean out the cup.

In forming the blank 1 a slot 6 is cut 105 therein close to the middle portion of the line *b*. This slot is adapted to receive the projecting end portion of an inclined staple 7 driven into the tree at a point below the cut therein. Moreover the cup can be readily lifted off of the staple simply by placing the hand under the cup and grasping the 110

bottom portion thereof. Both the removal of the cup and the replacing thereof upon the staple can be effected quickly.

In order that the turpentine may be accurately directed into the cup, an apron, such as shown in Fig. 1, may be employed. This apron, 8, may be provided with converging upstanding flanges 7' for directing turpentine into the top of the cup.

It will be seen that the entire device constituting the present invention can be very cheaply manufactured and is capable of long continued use because the folded parts are held securely together under all conditions.

By fastening the folds together at the upper corners of the cup by means of the clips 5 the seams are not only prevented from gaping under the conditions hereinbefore mentioned but the folds are permitted to spread open to a slight extent below the clips 5 should water freeze within the cups. Heretofore turpentine cups have often been permanently injured by bursting when subjected to the expansive action of freezing water contained within them. The structure herein described, however, permits more or less expansion of the cup without resulting in such injury.

What is claimed is:—

1. A turpentine cup formed in a single blank of sheet metal folded longitudinally to form front and rear walls, the sides of the blank being bent along diagonal lines to form triangular folds bearing upon the back wall, a flap formed along the upper edge of the back wall and lapping and holding the triangular folds, and clips formed by the ends of the flap and engaging the front wall at the sides thereof.

2. A turpentine cup formed in a single blank of sheet metal folded to form front and rear walls merging together along curved lines, the sides of the blank being folded along diagonal lines to form triangular folds bearing upon one wall of the cup a flap for holding the folds against gaping, and clips formed by the ends of the flap for engaging the sides of the cup to secure the flap in holding position.

In testimony that I claim the foregoing as my own, I have hereto affixed my signature in the presence of two witnesses.

DEMARIAN L. O'NEAL.
